may be turned to the position seen in Figure 2 in which it is parallel with the handle. The sleeve member may be turned around the parts 5 and 30 to desired positions for using the foot rest. It 5 will be seen that this sleeve member greatly strengthens the joint of parts 5 and 30.

The invention being intended to be pointed out in the claims, is not to be limited to or by details of construction of the particular embodiment 10 thereof illustrated by the drawing or hereinbefore described.

We claim:

1. In a horticultural implement, in combination: a tool element and an elongated handle element pivotally connected for relatively turning movement about an axis transverse thereto; a latch pivotally mounted on the handle element turnable inwardly to a position engaging the tool element for holding said elements against such 15 relative movement; a collar on the handle element turnable therearound and slidable therealong to and from a position engaging the latch for holding the same in its said position; a foot rest pivotally mounted on the collar for turning move- 20

ment to and from operative position transverse the axis of the handle element and turnable with the collar to angular positions about said axis.

2. In a horticultural implement, in combination: a tool element and an elongated handle element pivotally connected for relatively turning movement about an axis transverse thereto; a latch pivotally mounted on the handle element turnable inwardly to a position engaging the tool 5 element for holding said elements against such relative movement; a collar on the handle element turnable therearound and slidable therealong to and from a position engaging the latch for holding the same in its said position; a lever 10 fulcrumed on the collar having a pedal arm and an arm adapted to engage the handle element under pressure on the pedal arm for holding the collar against movement relatively thereto, the lever being turnable with the collar to angular 15 positions about the axis of the handle element in the absence of said pressure on the pedal element. 20
